BED BOTTOM

Burtnett McIntosh, Floral Park, N. Y., assignor to Frank A. Hall & Sons, New York, N. Y.

Application June 6, 1933, Serial No. 674,481

5 Claims. (Cl. 5—69)

My present invention relates to bed bottoms and bed springs, and aims to provide certain improvements therein. More particularly it relates to articulated bed bottoms designed for hospital use.

An object of my invention is to provide a bed bottom which will have greater cushioning qualities than the link fabric bottoms conventionally used in hospital beds and which will permit articulation of the various sections while affording maximum comfort to a patient lying thereon. A further object is to provide a bed bottom or bed spring composed of a composite coil spring fabric and link fabric which will be non-sagging, non-stretchable, and which will always return to its initial shape when relieved of compression forces acting thereon. A further object is to provide a bed bottom or bed spring wherein coil springs are relied upon to provide the cushioning action while a flexible link fabric is relied upon to support the weight of the person lying on said bed bottom.

The foregoing and other objects of my invention, which will become apparent from a detailed description which follows, I accomplish by providing a bed bottom which is preferably composed of coiled cushioning springs arranged in rows which are held in assembled relation by flexible top and bottom fabrics, which, in turn, preferably consist of links and clips extending transversely of the bed bottom and connected to the sides thereof by helical springs, said flexible fabrics being connected respectively to the top and to the bottom convolutions of the cushioning coils in a manner to permit free flexing of the bed bottom in all directions and a folding action thereof transversely of its length. The invention will be better understood from the detailed description, when considered in conjunction with the accompanying drawings showing a preferred embodiment of my invention, and wherein:

Figure 1 is a longitudinal section through a bed bottom embodying my invention, said section being taken substantially along the plane of the line 1—1 of Fig. 2.

Fig. 2 is a top plan view of a bed bottom embodying my invention.

Fig. 3 is an enlarged transverse section of a portion of a bed bottom embodying my invention, said section being taken substantially along the plane of the line 3—3 of Fig. 4.

Fig. 4 is a top plan view of a portion of the bed bottom taken substantially along the plane of the broken line 4—4 of Fig. 3.

Fig. 5 is a sectional detail taken substantially along the plane of the broken line 5—5 of Fig. 3.

Fig. 6 is a sectional detail taken substantially along the plane of the line 6—6 of Fig. 4.

Referring to the drawings wherein I have shown my invention applied to an articulated bed bottom mounted upon a bedstead A, let B indicate the ends of the bed bottom frame which consists of a central or intermediate fixed section having side members C, an articulated back-supporting section having side members D hingedly connected to the members C at c, a thigh-supporting section having side members E hingedly connected to the members C at 2c, and a leg-supporting section having side members F which are hingedly connected to the members E at e.

Each of the bed bottom sections is preferably formed with a resilient cushion consisting of a plurality of double volute springs G disposed in rows in axially spaced relation, said rows extending transversely of the bed bottom. The end convolutions of each of the springs G is formed with substantially straight offset portions g at diametrically opposite parts of said convolutions, and the adjacent springs of adjacent rows of springs are hingedly connected together at both their tops and bottoms through the medium of clips H having portions thereof engaging around said offset portions g. The clips H are each formed with an elongated central opening h for receiving the turned back ends of links J which serve to connect the clips in rows transversely of the bed bottom, and thus function to hold the springs G in an assembled, readily foldable, cushioning fabric.

The clips H and links J of each row may be defined as a strand, and the terminal links of each strand are pivotally connected to plates K through openings k therein. Said plates K are preferably formed with a plurality of such openings suitably spaced therein, and the plates at the ends of each strand are longitudinally connected together through links J', the ends of said links engaging through said openings k in said plates.

The flexible link fabrics thus provided by the clips H, links J, perforated plates K and links J', are resiliently supported by the side members C, D, E and F, respectively, of the bed bottom sections, through the medium of helical springs L and M which are alternately arranged and connected to said side members by an end loop of each of said springs engaging in an opening in said side members. The springs L are designed to resiliently support the flexible link fabric disposed at the top of the volute springs G, and

connected thereto, while the springs M serve to support the flexible link fabric disposed at the bottom of the volute springs G and connected thereto. To provide a connecting medium between the upper link fabric and the springs L and to reinforce said fabric longitudinally and more equally distribute the supporting action of the springs therefor along its longitudinal dimension, the top link fabric is provided with a supplemental longitudinal strand consisting of links J' and plates K, which strand is connected to the longitudinal strand at the terminal ends of the transverse strands through the medium of links J², it being understood that the various links are all non-detachably connected to the plates K by having the ends of said links engaging through the openings in said plates and being bent back upon themselves in a well known manner to permit of limited pivotal action between said parts. For suitably resiliently supporting the flexible link fabric at the bottom of the spring G, the terminals of the adjacent transverse strands are connected to springs M through the medium of V-shaped links J³, the anchoring loop at the end of the spring M engaging in the bights of said V's and the free ends of said V's engaging in openings k in the plates K, as best shown in Fig. 5.

Between the fixed intermediate section of the bed bottom and the back-supporting section and the thigh-supporting section, respectively, I prefer to leave a transverse space between the adjacent rows of springs G to permit free flexing of the cushioning springs G without distortion as the bed sections are moved relatively to each other. To prevent the mattress from engaging within said upper space and being caught therein during the flattening out of the bed bottom, I provide helical springs N, the ends of which engage in the openings in the clips H. I may likewise provide one or more springs O between the end rows of springs G and the ends B of the frame for preventing the ends of the mattress engaging in the space between said ends and springs, which springs may also serve to provide a more equitable tension and resilient support for said end rows of springs, especially the springs of said rows that are disposed approximately midway between the sides of the bed bottom.

From an inspection of Fig. 3 it will be apparent that the double volute springs G normally hold the flexible link fabrics at the top and at the bottom of said springs in substantially parallel spaced and tensioned relation, and it will also be apparent that as the weight of a patient lying on said bed bottom compresses the springs G, the cushioning action afforded by said springs will be a maximum, since the weight of the patient is primarily borne by the link fabrics which are resiliently tensioned by the helical springs L and M. It will also be apparent that the weight of a patient when bearing upon the back-supporting section or the thigh-supporting section or the leg-supporting section when any of said sections are in inclined relation to the fixed section will be practically entirely borne by the top link fabric and the springs G will primarily function as a resilient cushion. Furthermore, because of the cooperative relation between the springs G and the link fabrics at the top and at the bottom thereof and the supporting helical springs L and M for said link fabrics, sagging and stretching of the cushioned bed bottom will be prevented, thereby not only prolonging the life of such bed bottoms, but also insuring maximum comfort for patients.

From the foregoing detailed description it will be appreciated that while I have shown and described a preferred embodiment of my invention and the manner in which the same is constructed and functions, I do not wish to be limited to said details of construction, since it will be apparent that the same may be varied without departing from the spirit of my invention. 80

What I claim is:

1. A bed bottom consisting of a frame and a resilient cushion supported wholly by two parallel elements of the frame, said cushion comprising a plurality of coil springs disposed in rows extending transversely to the supporting elements of the frame, clips hingedly connecting the springs of adjacent rows at their tops and bottoms respectively, links flexibly connecting the clips between the rows of springs at the tops and bottoms of the springs respectively, and helical springs connecting the terminals of the rows of links and clips to the supporting elements of the frame. 85
2. A bed spring or the like comprising a frame, a plurality of double volute springs disposed in rows in axially spaced relation, the end convolutions of said springs having substantially straight offset portions at diametrically spaced points, the offset portions of the springs extending in parallel relation to the rows of springs, clips hingedly connected to the springs of adjacent rows at both the tops and bottoms thereof at their offset portions, links connecting the clips between the respective rows of springs, secondary links connecting the terminal links at each end of the respective rows of links and clips, and resilient means connecting the link fabrics thus provided at both the tops and bottoms of the springs to the side members of the frame. 90
3. An articulated bed bottom comprising relatively movable sections having side frame elements through which the sections are hingedly connected together, each section having a plurality of rows of coil springs extending transversely to the side frame elements with their axes disposed substantially at right angles to the planes of the respective sections, the coil springs of adjacent rows of each section being connected together at their tops and bottoms respectively to form a cushion, and said cushion being resiliently supported wholly by the side frame elements of the respective sections. 105
4. An articulated bed bottom comprising relatively movable sections having side frame elements through which the sections are hingedly connected together, each section having a plurality of rows of coil springs extending transversely to the side frame elements with their axes disposed substantially at right angles to the planes of the respective sections, clips flexibly connecting the springs of adjacent rows together at their top and bottom convolutions respectively, links connecting the clips between adjacent rows of springs to provide articulated strands, and resilient means connecting the ends of said strands to the side frame elements of the sections whereby the coil springs are resiliently supported wholly by the side frame elements. 110
5. An articulated bed bottom comprising a fixed section and a movable section hingedly connected to the fixed section, each section having a resilient cushion consisting of flexible top and bottom articulated link fabrics and coil springs disposed in rows at right angles to the side frame elements disposed in between said fabrics with the end convolutions of the springs articulated 115
6. A bed bottom comprising a frame and a resilient cushion supported wholly by two parallel elements of the frame, said cushion comprising a plurality of coil springs disposed in rows extending transversely to the supporting elements of the frame, clips hingedly connecting the springs of adjacent rows at their tops and bottoms respectively, links connecting the clips between the rows of springs at the tops and bottoms of the springs respectively, and helical springs connecting the terminals of the rows of links and clips to the supporting elements of the frame. 120
7. A bed bottom comprising a frame and a resilient cushion supported wholly by two parallel elements of the frame, said cushion comprising a plurality of coil springs disposed in rows extending transversely to the supporting elements of the frame, clips hingedly connecting the springs of adjacent rows at their tops and bottoms respectively, links connecting the clips between the rows of springs at the tops and bottoms of the springs respectively, and helical springs connecting the terminals of the rows of links and clips to the supporting elements of the frame. 125
8. A bed bottom comprising a frame and a resilient cushion supported wholly by two parallel elements of the frame, said cushion comprising a plurality of coil springs disposed in rows extending transversely to the supporting elements of the frame, clips hingedly connecting the springs of adjacent rows at their tops and bottoms respectively, links connecting the clips between the rows of springs at the tops and bottoms of the springs respectively, and helical springs connecting the terminals of the rows of links and clips to the supporting elements of the frame. 130
9. A bed bottom comprising a frame and a resilient cushion supported wholly by two parallel elements of the frame, said cushion comprising a plurality of coil springs disposed in rows extending transversely to the supporting elements of the frame, clips hingedly connecting the springs of adjacent rows at their tops and bottoms respectively, links connecting the clips between the rows of springs at the tops and bottoms of the springs respectively, and helical springs connecting the terminals of the rows of links and clips to the supporting elements of the frame. 135
10. A bed bottom comprising a frame and a resilient cushion supported wholly by two parallel elements of the frame, said cushion comprising a plurality of coil springs disposed in rows extending transversely to the supporting elements of the frame, clips hingedly connecting the springs of adjacent rows at their tops and bottoms respectively, links connecting the clips between the rows of springs at the tops and bottoms of the springs respectively, and helical springs connecting the terminals of the rows of links and clips to the supporting elements of the frame. 140
11. A bed bottom comprising a frame and a resilient cushion supported wholly by two parallel elements of the frame, said cushion comprising a plurality of coil springs disposed in rows extending transversely to the supporting elements of the frame, clips hingedly connecting the springs of adjacent rows at their tops and bottoms respectively, links connecting the clips between the rows of springs at the tops and bottoms of the springs respectively, and helical springs connecting the terminals of the rows of links and clips to the supporting elements of the frame. 145
12. A bed bottom comprising a frame and a resilient cushion supported wholly by two parallel elements of the frame, said cushion comprising a plurality of coil springs disposed in rows extending transversely to the supporting elements of the frame, clips hingedly connecting the springs of adjacent rows at their tops and bottoms respectively, links connecting the clips between the rows of springs at the tops and bottoms of the springs respectively, and helical springs connecting the terminals of the rows of links and clips to the supporting elements of the frame. 150

connected to elements of said flexible fabrics, said flexible fabrics consisting of parallel strands of linked elements connected together at their terminals by secondary strands of linked elements disposed at right angles to the first recited strands, helical springs connecting the secondary strands of the linked elements to the side frame elements of the sections, and means between said resilient cushions at the hingedly connected sections of the bed bottom for preventing the mattress from catching therebetween during the articulation of the sections. 80
